(57) **CLAIM**

The ornamental design for a water sprinkler component, as shown and described.

DESCRIPTION

FIG. 1 is a perspective view of a water sprinkler component showing my new design;

FIG. 2 is a right side elevational view showing the design for the water sprinkler component of FIG. 1;

FIG. 3 is a left side elevational view showing the design for the water sprinkler component of FIG. 1;

FIG. 4 is a front elevational view showing the design for the water sprinkler component of FIG. 1;

FIG. 5 is a rear elevational view showing the design for the water sprinkler component of FIG. 1;

FIG. 6 is a top elevational view showing the design for the water sprinkler component of FIG. 1; and,

FIG. 7 is a bottom elevational view showing the design for the water sprinkler component of FIG. 1.

The broken line showing of portions of the water sprinkler component is included for illustrative purposes only and forms no part of the claimed design.
